UNITED STATES PATENT OFFICE.

ALVAH CLARENCE TEBBETTS, OF BOSTON, MASSACHUSETTS.

DESIGN FOR A LIP GUARD AND PROTECTOR.

SPECIFICATION forming part of Design No. 29,467, dated October 11, 1898.

Application filed September 7, 1898. Serial No. 690,441. Term of patent 3½ years.

To all whom it may concern:

Be it known that I, ALVAH CLARENCE TEBBETTS, of Boston, in the county of Suffolk and State of Massachusetts, have invented and produced a new and original Design for Lip Guards and Protectors, of which the following is a description.

The accompanying drawings are to be taken as forming a material part of this specification.

Figure 1 is a perspective view, looking from the inside, of a lip guard and protector, showing my new design. Fig. 2 is a similar view looking from the outside.

As shown in the drawings, the leading or material feature of my design consists of the segmental curvature in cross-section of both the outside body part *a* and the inside lip *b* and the substantially U-shaped bend or curve

in vertical section at the point of junction *c* 20 of the lip *b* with the body part *a*. From the point of junction *c* to their extremities the body and lip parts diverge slightly each from the other. The inner lip *b* is provided with perforations or holes *d*. 25

Having thus fully described my new and useful design, I declare that what I claim is—

The design for a lip guard and protector, substantially as herein shown and described.

In testimony whereof I have signed my 30 name to this specification, in the presence of two subscribing witnesses, this 3d day of September, A. D. 1898.

ALVAH CLARENCE TEBBETTS.

Witnesses:

ARTHUR W. CROSSLEY,
ANNIE J. DAILEY.
